CLAIM

The ornamental design for a combined bottle neck and closure, as shown.

DESCRIPTION

FIG. 1 is an isometric view of a combined bottle neck and closure showing my new design.

FIG. 2 is a top plan view of the closure shown in FIG. 1.

FIG. 3 is a bottom plan view of the closure shown in FIG.

1.

FIG. 4 is a top plan view of the bottle neck shown in FIG.

1.

The broken line showing of a bottle is for illustrative purposes only and forms no part of the design.
